UNITED STATES PATENT OFFICE.

WILLIAM D. THOMPSON, OF DETROIT, MICHIGAN, ASSIGNOR TO HUTCHINS CAR ROOFING COMPANY, OF DETROIT, MICHIGAN, A CORPORATION OF MICHIGAN.

CAR END.

Application filed November 20, 1922. Serial No. 602,091.

To all whom it may concern:

Be it known that I, WILLIAM D. THOMPSON, a citizen of the United States of America, residing at Detroit, in the county of Wayne and State of Michigan, have invented certain new and useful Improvements in Car Ends, of which the following is a specification, reference being had therein to the accompanying drawings.

- 10 The invention relates to car body construction of that type more particularly designed for use in car ends and composed of a series of separately pressed paneled plates rigidly attached to each other. Each of 15 the paneled sections is formed with the greater part of the metal lying in two parallel planes, being connected by obliquely extending portions forming a truss. It is usual to provide such end plates with a 20 wooden lining and the boards composing such lining are laid against the metal in one of said planes.

It is the object of the present invention to facilitate the placing of the lining flush 25 with the inner face of the metallic plate and to this end the invention consists in the construction as hereinafter set forth.

In the drawings:

Figure 1 is a vertical longitudinal section 30 through a portion of the car embodying my invention;

Figure 2 is a horizontal section there- 35 through.

The individual pressed sheet metal plates A, A', etc. are each formed with a central panel B, which is in a plane parallel to the plane of the marginal portions C and connected therewith by obliquely inclined portions D. The adjacent plates have overlapping portions E and F which are rigidly secured to each other by rivets G. Thus the composite plate is strongly trussed and is high in rigidity.

It is usual to provide a wooden lining 40 which protects the goods within the car

from direct contact with the metallic plate or any moisture condensation formed thereon. This lining is formed of a series of matched boards H arranged adjacent to the inner plane of the metallic plate and secured by nailing to strips I extending in the spaces formed by the panels. To permit such lining plates to lie in close contact with the inner face of the metallic plate, the overlapping portions E and F are slightly offset as shown. The amount of deflection is just sufficient to provide clearance for the heads of the rivets G, so that said rivets will not obstruct the boards H. This is advantageous in that the lining has a firm bearing against the metallic plate and the necessity of recessing or cutting away the lining boards to clear the rivets is avoided.

What I claim as my invention is:

1. In a car body construction, a series of 55 pressed sheet metal paneled plates having overlapping adjacent edge portions riveted to each other, said overlapping portions being laterally offset to provide clearance for the rivet heads. 60

2. In a car body construction, a series of 65 pressed sheet metal paneled plates having overlapping adjacent edge portions riveted to each other, said overlapping portions being offset from the base plane of said plates 70 to provide clearance for the rivet heads, and a lining lying flush with said base plane. 75

3. In a car body construction, a series of 80 pressed sheet metal paneled plates having the panels thereof and the marginal portions in spaced parallel planes connected by transversely extending portions, a lining lying flush with the marginal portions of 85 said plates, and overlapping portions of said plates riveted to each other and laterally offset to provide clearance for the rivet ends without interference with said lining.

In testimony whereof I affix my signature.

WILLIAM D. THOMPSON.
